UNITED STATES PATENT OFFICE

2,561,919

WARPING MILL

Peter Florjancic, Montreux, Switzerland, assignor
to "Patra" Patent-Administration and Trading
Co., Vaduz Liechtenstein, (reg. trust)

Application January 19, 1948, Serial No. 3,121
In Switzerland May 12, 1947

5 Claims. (Cl. 28—31)

1

The present invention relates to a warping mill, the principal objects of the invention being: first to overcome some disadvantageous features of known warping mills and especially to avoid different tensions of separate threads in the winding or reeling of yarn, thread or fibrous material to constitute warp in weaving operations; and to provide a comparatively simple, durable and efficient warping-mill for producing a superior resultant material and in such state or condition as to furnish a uniform type or quality of warp; second to provide a warping-mill with attachments or devices adjustably connected with the crossarms thereof and so arranged that the thread or yarn in the reeling operation is built up in regular lays onto one another into substantially truncated cones and in such a manner that in the formation of one of such figures or forms it will become a form or guide for the building or laying up in regular sequence of a series of such cone-shaped deposits of yarn or fibrous material onto the respective cross arms of the reel during the rotation thereof until the spools or bobbins of the creel or frame have been depleted or until the cross-arms of the reel have been completely covered and in such manner as to present a smooth cylindrical surface, when the same is transferred in such state or condition to a beam to constitute warp for use in the weaving operation; third to provide a warping mill adapted to cone the yarn or thread thereon which is provided with mechanism adapted to move automatically step by step in one direction in the laying or building up of the thread or yarn into cone-shaped figures or forms thereon; fourth, to provide a warping mill adapted to improve the winding of the yarn or thread and with the absence of broken threads or of having to stop the reel to take up and unite broken ends in the unwinding of the same onto a beam to become warp, the said mechanism being so constructed and arranged that the warping and beaming operations are appreciably improved and a superior quality of warp for weaving is obtained, due to the uniformity of tension maintained throughout the winding or reeling of the yarn or fibrous material.

The present invention stated in general terms, consists of a warping mill provided with attachments adjustably connected therewith and so arranged that the yarn or fibrous material is formed in regular and united sequence into cones presenting a smooth cylindrical surface for transfer therefrom to a beam to become warp.

Said invention further consists in the improvements hereinafter described and claimed.

2

The nature, general features and scope of the invention will be more fully understood from the following description taken in connection with the accompanying drawing which forms a part of the description and wherein a diagrammatical elevation of an embodiment of the warping mill according to invention, partly in a sectional view, is shown in its position at the beginning of a normal reeling operation.

10 As can be seen from the drawing, a drum 1 is supported on an axle 2 which in turn is rotatably and slidably supported by bearings 3, 4. Drum 1 and axle 2 are keyed to each other so that the drum rotates with the axle 2. A gear 5 is secured to the axle 2 and engages with a pinion 6. This latter is fitted on a shaft 7 which can be rotated by means not shown in the drawing. When the shaft 7 is rotated, the axle 2 and the drum 1 will also be rotated. To displace the drum longitudinally with respect to the bearings, a bushing 8 is fixed onto the right hand end of the axle 2 as viewed in the drawing, and this bushing is provided with an internal screw-thread which engages with a threaded spindle 9. The spindle 9 is rigidly connected to a worm gear 10 which engages with a worm 11. If the driving shaft 7 is rotated, the pinion 6 and gear 5 transmit the rotation to the axle 2 and drum 1. Due to the irreversibility of the worm gearing 10—11, the threaded spindle 9, which is rigidly secured to worm gear 10, is held stationary and the bushing 8 which is rotatable with axle 2, unscrews from the threaded spindle 9, thus imparting to axle 2 an axial movement in the left hand direction, so that a cone shaped section is reeled on the drum 1. When the driving shaft 7 is stopped and the worm 11 is rotated to cause rotation of worm gear 10 and threaded spindle 9, however, the bushing 8 is screwed onto the spindle 9 thus imparting to the axle 2 and drum 1 an axial movement without rotation in the right hand direction bringing the machine into its initial position wherein it is ready to receive a further section of yarn.

45 Since the axle 2 and the gear 5 secured thereto are movable axially of the bearing 3 and 4, means (not shown) are provided to allow movement of the pinion 6 and shaft 7 to prevent disengagement of the gear and pinion.

50 Sixteen bell-crank levers 12 are uniformly distributed around the periphery of the drum 1 at one end thereof and are pivotally mounted on pins 13. One arm of the bell-crank levers 12 is forked and a pin 14, fitted on a nut 15, is located 55 between the two prongs of the fork. The nuts 15

are mounted on threaded spindles 16 which are supported in the drum wall 17 so that they can rotate but are incapable of axial displacement. The lefthand end of each spindle 16 carries a sprocket 18 and a chain 19 is laid over all the sprockets 18. One of the threaded spindles 16 is provided with a handwheel 20. Upon rotation of this handwheel, the threaded spindle 16 and sprocket 18 associated therewith are rotated, the rotation of the sprocket being transmitted through the chain 19 to all the other sprockets 18 so that same are rotated to exactly the same extent. As can at once be seen, it is thus possible to adjust the inclination of the outwardly projecting arms of the bell-crank levers 12 simultaneously and to the same extent.

What I claim is:

1. Warping mill with a rotatably supported drum, and with a plurality of bell-crank levers adjustable simultaneously and to the same extent, said bell-crank levers being pivotally supported at one end of the drum, the bell-crank lever arms directed towards the axle of the drum being forked, a pin fixed on a nut entering between the two prongs of the fork-shaped lever arm, the whole being such that the nut is adjustable in the direction of the drum axis by means of a coordinated threaded spindle.

2. Warping mill with a rotatably supported drum, and with a plurality of bell-crank levers adjustable simultaneously and to the same extent, said bell-crank levers being pivotally supported at one end of the drum, the bell-crank lever arms directed towards the axle of the drum being forked, a pin fixed on a nut entering between the two prongs of the fork-shaped lever arm, the whole being such that the nut is adjustable in the direction of the drum axis by means of a coordinated threaded spindle, each threaded spindle carrying a sprocket at one end and a chain laid over all these sprockets.

3. Warping mill with a rotatably supported drum, and with a plurality of bell-crank levers adjustable simultaneously and to the same extent, said bell-crank levers being pivotally supported at one end of the drum, the bell-crank lever arms directed towards the axle of the drum being forked, a pin fixed on a nut entering between the two prongs of the fork-shaped lever arm, the whole being such that the nut is adjustable in the direction of the drum axis by means of a coordinated threaded spindle, each threaded spindle carrying a sprocket at one end and a chain laid over all these sprockets, one of the threaded spindles being provided with a 55 handwheel.

4. Warping mill with a rotatably supported drum, and with a plurality of bell-crank levers adjustable simultaneously and to the same extent, said bell-crank levers being pivotally supported at one end of the drum, the bell-crank lever arms directed towards the axle of the drum being forked, a pin fixed on a nut entering between the two prongs of the fork-shaped lever arm, the whole being such that the nut is adjustable in the direction parallel to the drum axis by means of a coordinated threaded spindle, each threaded spindle carrying a sprocket at one end and a chain laid over all these sprockets, one of the threaded spindles being provided with a handwheel, the threaded spindles being supported in the drum so that they can rotate but not be displaced axially.

5. Warping mill of the sectional type comprising in combination a rotatably supported drum provided with a plurality of bell crank levers adjustable simultaneously and to the same extent, said bell crank levers being pivotally supported at one end of said drum, a pair of coaxial bearings, an axle rotatably mounted within said bearings and axially displaceable therein, said drum being fixedly mounted on said axle, means for axially displacing said axle upon rotation thereof and for axially displacing said axle in the reverse direction without rotation, said means comprising a drive shaft arranged parallel to said axle, a pinion secured to said shaft, a gear secured to said axle meshing with said pinion, a bushing having an internal thread rigidly secured to one end of said axle, a threaded spindle engaged with the thread in said bushing, a worm gear secured to the outer end of said spindle, and a worm meshing with said worm gear for rotating same independently of said drive shaft.
